SHOE SEWING MACHINE

George A. Miner, Manchester, N. H., assignor to
 United Shoe Machinery Corporation, Flemington, N. J., a corporation of New Jersey

Application September 19, 1945, Serial No. 617,349

3 Claims. (Cl. 112—51)

1

The present invention relates to shoe sewing machines and is herein illustrated as embodied in a machine for simultaneously sewing together the edges of an upper, an insole, and a relatively wide strip of covering material, to enable covering a platform type sole on a shoe by wrapping the unsewed edge of the strip about the edge of the sole.

In sewing a platform sole edge covering strip to a shoe, the usual practice is to guide the strip in such relation to the machine that the seam will pass through one edge of the strip while the loose portion of the strip is left free to be wrapped about the edge of the platform sole, sometimes referred to briefly as the platform. In a curved hook needle shoe sewing machine there is little if any available space for the addition to the machine of a bulky guide ordinarily required to direct the sole edge covering strip or wrapper to the sewing point. Also, platform sole edge covering strips or wrappers are relatively flexible and are not susceptible to easy and accurate control or direction of movement.

In guiding a sole edge covering strip or wrapper into sewing position, it is desirable to sew the strip as close to its edge as is practicable, leaving free as great a width of the strip as possible for subsequent wrapping about the edge of the sole. With excessive flexibility in a covering strip, accurate control or direction cannot be obtained merely by confining the strip throughout its entire width, the rigidity of the strip being insufficient to maintain proper guiding action. Furthermore, a platform edge covering strip or wrapper frequently is cut with a non-uniform width to fit the edges of a platform sole or heel lift having varying degrees of thickness throughout the length of the shoe, thus increasing still further the difficulty in controlling the strip.

A method and machine for controlling a platform edge covering strip of variable width while being guided into sewing position on a shoe is disclosed in an application for United States Letters Patent Serial No. 608,644, filed August 3, 1945, in the name of Everett E. Murphy. The method and machine of that application are effective for the purposes intended, particularly where the space requirements in the machine are such that the covering strip guide causes the covering strip to be directed accurately along one edge with the other edge of the strip extending downwardly away from the sewing point in a natural unwrinkled condition. In certain types of sewing machine, the shoe is so presented to the machine that, while attaching a platform edge

2

covering strip to the shoe, the strip must project upwardly away from the sewing point instead of downwardly as in the machine of the Murphy application, and other requirements of space in the machine and construction of the shoe prohibit the use of a strip guiding enlargement along the sewing edge of the strip, as in the Murphy machine.

Accordingly, an object of the present invention is to provide a shoe sewing machine having a platform edge covering strip or wrapper guide which will enable easy application of the strip to a shoe and will afford accurate control of the strip without the exercise of unusual skill or ability on the part of the operator or of prior treatment for the strip as required by the machine of the Murphy application above referred to.

In the embodiment of the present invention, a machine for sewing a platform edge covering strip to a shoe is provided having a work piercing needle properly arranged to operate upon the shoe, and a covering strip guide formed with one open edge and a gaging abutment for the opposite edge of the covering strip substantially in line with the needle path, in which guide there is means for crowding the strip against the abutment comprising a friction wheel acting on the covering strip in advance of the sewing point and adjustable means for maintaining the wheel in contact with the strip so that the force required to cause the friction wheel to slide along the strip as the wheel rotates may be changed readily with strips of different degrees of stiffness.

Other features of the invention consist in the devices, combinations and arrangements of parts hereinafter described and claimed, the advantages of which will readily be understood from the following description taken in connection with the accompanying drawings, in which

Fig. 1 is a view in right side elevation of portions surrounding the sewing point of a shoe sewing machine embodying the present invention, with the parts of a shoe operated upon shown in section;

Fig. 2 is a view in left side elevation of the same portions of the machine illustrated in Fig. 1;

Fig. 3 is a plan of the same portions of the machine, as viewed in the direction of the arrow III in Fig. 2;

Fig. 4 is a rear elevation of the same portions of the machine looking in the direction of the arrow IV of Fig. 2;

Fig. 5 is a plan of the portions of the machine and work operated upon, as viewed in the direction of the arrow V of Fig. 2;

Fig. 6 is a sectional view of a portion of a shoe after the covering strip has been sewed on by the machine embodying the present invention; and

Fig. 7 is a corresponding view of a portion of the shoe after completion.

The illustrated machine is intended to operate upon and to secure together the marginal portions of a shoe upper 10, a flange portion of a sock lining or light-weight flexible insole 12, and one edge of a sole edge covering strip or wrapper 14, with their edges in registry. To complete the construction of a shoe with the parts assembled in this way, the space inside the flange of the sock lining or insole 12 is filled with a fibrous platform 16, and the free flexible edge of the covering strip is wrapped around the edge and over the bottom of the platform to conceal the stitches connecting the parts together. Thereafter, the shoe is completed with the attachment of an outsole 18 by any convenient means, such as cement or through-and-through stitches. In case cement is employed to attach the parts of the completed shoe, it is unnecessary to remove the last, indicated at 20, on which the shoe is assembled.

The machine herein illustrated for securing the sock lining, upper and edge covering strip together is of the type disclosed in United States Letters Patent No. 1,169,909, granted February 1, 1916, in the name of Fred Ashworth, and includes the usual lockstitch forming devices including work piercing instruments, the curved hook needle of which is indicated at 22 and the curved awl at 24. The operating path of the needle and awl, as illustrated by the dot-dash line 26 of Fig. 2, is arranged to intersect the flange of the sock lining or insole 12 and the registering marginal portion of the upper 10 when the parts are presented to the machine with the flange and upper disposed between a work support 28 and a presser foot 30 actuated alternately to clamp and release the work as the stitches are inserted successively.

To direct the edge covering strip or wrapper 14 into the seam inserted by the stitch forming devices of the illustrated machine, particularly where the covering strip is composed of relatively light, flexible material of a width varying from the forepart to the heel portion of a shoe, and where relatively high wedge heels or lifts are employed along the latter portion of a shoe, the presser foot 30 is provided with an open edged guide having suitably bent parallel strip confining plates 32 and 34 located in advance of the sewing point in the machine and spaced sufficiently to receive between them the covering strip. The space between the plates has its open edge directed away from the sewing point, and a gaging abutment 36 is provided at the end of the space for one edge of the covering strip substantially in line with the needle and awl path. To avoid interference with the operating parts of the machine and to provide a convenient arrangement in which the covering strip is easily and quickly brought in a widthwise direction into contact with the gaging abutment 36 of the guide, the guide is arranged to maintain the strip in an inclined position with its free outer edge projecting upwardly at an angle away from the sewing point. The natural position of the strip within the guide, accordingly, is with its lowermost edge in contact with the gaging abutment, where it may readily be directed along the seam

line into registry with the other parts of the shoe being operated upon. The presser foot which comprises an integral part of the guide is secured to a presser foot lever 38 by means of loosely fitting screws 40 enabling the guide to be properly adjusted to give the desired results.

In order to insure uniform guiding action of the covering strip under all conditions, the strip guide of the present invention is provided with 10 novel means acting to crowd the strip downwardly against the gaging abutment as the strip is drawn through the guide toward the sewing point. To obtain a crowding action of the strip against the abutment, the plate 34 of the strip guide is formed with a slot 42 (Fig. 5) to receive the periphery of a friction wheel 44 engaging the strip and mounted to rotate about an axis inclined at an acute angle to the length of the abutment 36 and the line of the seam. Thus, during movement of the strip through the guide, the wheel 44 tends to rotate and to direct the strip against the abutment. As soon as the strip engages the abutment, a continued edgewise crowding force is applied in the direction of the arrow 46 of Fig. 3 whenever the strip moves in the direction of feed indicated by the arrow 48. The edgewise crowding action is proportionate to the sliding friction of the wheel along the strip, the mounting of the wheel being such as to enable this friction to be varied as conditions demand.

The mounting for the friction wheel 44 comprises a spindle 50 about which the wheel rotates, a spindle supporting yoke 52 having a side opening 54 to receive the wheel, a hinge pin 56 at one end of the yoke on which the yoke may pivot to enable the wheel to move toward and from the strip in the guide, and a bracket 58 secured to the plate 34 for supporting the hinge pin 56 between a pair of spaced lugs on the bracket. 40 To enable the pressure of the friction wheel to be maintained on the covering strip or wrapper regardless of thickness, the guide plate 34 has projecting at right angles therefrom a threaded stud 60 passing through a perforation in the yoke 52 and receiving a coil spring 62 compressed between the outer surface of the yoke and an adjustable thumb nut 64. The length of the spring 62 is such as to maintain a substantially constant yielding action of the friction wheel against the covering strip for any practical variations of strip thickness. With strips of different qualities and compositions, however, there may be wide variations in the stiffness of the strips so that, with an extremely flimsy strip, a very light crowding action only is required to maintain the strip in engagement with the gaging abutment 36. Accordingly, with strips of different degrees of stiffness, it is necessary to adjust the thumb nut 64 to limit the frictional and crowding action of the wheel 44.

With the use of the strip guide thus described, sole edge coverings may be sewed to shoes under a wide variation of conditions both in characteristics of the shoe and of the coverings. The guide is conveniently located, and the covering strip may be introduced laterally within the guide without the necessity of inserting first the end of the strip. Furthermore, the guiding action is readily maintained where the stiffness of the strip requires an increase or a decrease of the guiding force imparted to the strip in accordance with the ability of the strip to resist the forces applied to it during sewing operations.

The nature and scope of the invention having

been indicated and a particular embodiment having been described, what is claimed is:

1. A machine for sewing to a shoe a platform edge covering strip having a work piercing needle arranged to penetrate the marginal portion of the shoe, and a guide formed with one open edge and an abutment to engage the covering strip and direct it into the path of the needle, in combination with means acting on the covering strip in advance of the sewing point to crowd the strip against the abutment in the guide comprising a friction wheel mounted to rotate and slide along the surface of the covering strip transversely of its length, and adjustable means for yieldingly maintaining the friction wheel in contact with the strip to enable the force required to cause the wheel to slide along the strip to be changed with strips of different stiffness.

2. A machine for sewing to a shoe a platform edge covering strip having a work support, a presser foot, a work piercing needle arranged to penetrate the marginal portions of the shoe engaging the work support, a pair of parallel plates forming an open edged guide on the presser foot with the open edge directed away from the sewing point, and an abutment in the guide to engage the covering strip, in combination with a friction wheel mounted for rotation on one of the plates with its periphery entering a slot in said plate to engage the covering strip between said plates in advance of the sewing point, said wheel having its axis inclined at an acute angle to the line of the seam inserted by the needle to cause the covering strip to be crowded against the abutment in the guide during sewing operations with a force corresponding to that required to induce relative sliding movement between the wheel and strip, and adjustable means for yieldingly maintaining the friction wheel in contact with the strip to enable the force required to cause the wheel to slide along the strip to be changed with strips of different stiffness.

3. A machine for sewing to a shoe an edge covering strip having a work support, a presser foot, a work piercing needle arranged to penetrate the marginal portions of the shoe engaging the work support, a pair of parallel plates forming an open edged guide on the presser foot with the open edge directed away from the sewing point, and an abutment in the guide to engage the covering strip, in combination with a friction wheel mounted for rotation on one of the plates with its periphery entering a slot in said plate to engage the covering strip between said plates in advance of the sewing point, said wheel having its axis inclined at an acute angle to the line of the seam inserted by the needle to cause the covering strip to be crowded against the abutment in the guide during sewing operations with a force corresponding to that required to induce relative sliding movement between the wheel and strip, and adjustable means for yieldingly maintaining the friction wheel in contact with the strip to enable the force required to cause the wheel to slide along the strip to be changed with strips of different stiffness.
